UNITED STATES PATENT OFFICE.

ARTHUR C. LA COUR, OF MIDWEST, WYOMING.

PUMPING MECHANISM.

Application filed December 16, 1925. Serial No. 75,776.

This invention relates to improvements in oil well pumping mechanism. It pertains particularly to the combination of a normally stationary swab within the usual casing of an oil well pumping mechanism, and oil-elevating pumping means.

The object of my invention is to provide a swab, preferably of an elastic type, snugly fitting within the said casing adapted to maintain a fixed position during pumping operations but which, when the pumping mechanism is withdrawn from the casing, will effect the removal of matter, such as paraffine, sand and the like, that naturally adheres to the casing walls.

Still another object is that of providing within the casing a normally stationary swab through the center of which a tubular portion of the pumping mechanism may reciprocate, the fluid operated upon passing up through the swab, or rather the said tubular portion, during the movement of the latter.

In order that the objects, together with the results obtained from my construction may be better understood before describing such construction in detail, it may be stated that it is well known that after long continued pumping of the oil the casing has accumulated a considerable quantity of heavy matter, such as paraffine, which adheres to the walls of the casing and gradually constricts the bore thereof until the pumping operation must be stopped to permit the clearing of said casing to reestablish a free flow of the pumped medium.

Heretofore it has been necessary to withdraw the entire train of pumping connections and then to send a special swab down through the casing, and carried on a special cable, to clear out the casing before said train of connections can be used for further effective work. Due to this method of freeing the tube it is seen that there is first involved a withdrawal of the said connections, the insertion of the swab and continued manipulations thereof followed by the replacing of such connections before proper working conditions can be restored, involving a cost of at least thirty-five dollars per day depending upon the conditions and the depth of the well.

My apparatus is illustrated in the accompanying drawing wherein a preferred arrangement is shown and wherein,

Figure 1 is a longitudinal or vertical section of a casing showing my arrangement

therein, parts of which are also shown in longitudinal section.

Figure 2 is an elevation of a swab shown in Figure 1 and as enclosed in the casing 60 shown in section.

Figure 3 is an elevation of portions of a pump rod.

Figure 4 is a transverse section of a caging and valve on line 4-4, Figure 1, and 65

Figure 5 is also a transverse section of a caging on line 5-5, Figure 1.

In the figures the numeral 1 designates a part of the casing through which the oil is to be raised, and though not so shown, is connected in any usual manner to a pump barrel, not shown, forming part of such pumping outfit, and in which the usual lifting valves are housed, but not shown since well known, the same lying near the bottom of the well 75 while the parts carrying the same extend up into the casing 1 and may have attached thereto a rod 2, Figures 1 and 3, said rod having at its lower end an internally threaded enlargement 3, for example, and having at 80 its upper a threaded extension 4. When thus constructed any number of said rods may be connected together answering as the pumping connections together with my arrangement now to be described.

Screwed upon one of the rods 2, as in Figure 1, is a stem 5 having an enlargement 6 threaded to receive the portion 4 of said rod. The upper end of the stem 5 carries an open cage 7, a cross section of which is shown in Figure 5, there being screwed into a part 8 of said cage 7 a length of tubing 9 surmounting which is a seat 9' and a cage 10, the said seat within the said cage receiving a ball-valve 11, for example. The upper portion of the cage terminates in a stem 12 threaded to receive the lower end of one of the rods 2 described, it being thus seen that the said tubing 9 and its parts are interposed between two of the said rods 2 at 100 the desired position with relation to the mentioned pump barrel, not shown.

The swab included in my invention is shown at 13 in Figures 1 and 2 and is preferably of rubber or equivalent elastic type 105 adapted to snugly fit within the casing. It has a central longitudinal bore 13' and receives a length of tubing 14 within which the tubing 9 is permitted to reciprocate in a smooth and snug working fit. The ends of the swab are each preferably fitted with a cap 15 and upon the lower end of the tubing

14 is screwed a nut 16 which bears against the cap 15 at that end. The upper end of the tubing 14 also receives a nut 17 spaced from the upper cap 15 and a coil spring 18 5 is interposed between said nut and cap. Surrounding the tube 9 and lying between the cage 7 and the swab is a coil spring 8' which rests upon the cage but terminates preferably in spaced relation to the swab.

10 The tubing 9 and the series of rods 2 constitute a continuous pump rod extending throughout the casing 1 and it is to be understood that in the reciprocations of the same the tubing 9 moves up and down within the 15 swab-tubing 14, the swab remaining stationary, "freezing" to said casing 1.

The column of oil is raised within the casing in the usual manner and in the reciprocations of the tubing 9 it flows into the 20 cage 7 and up through said tubing and out beneath and above the ball-valve 11 in the cage 10, being lifted bulk by bulk.

When the casing becomes coated and clogged with the adhering matter in such 25 manner as to interrupt the free flow of oil, the line of rods is withdrawn from said casing carrying with it the swab, which, in fitting snugly, will completely clear the casing at one action so that the replacement of the 30 mechanism permits operations to proceed at once resulting in reducing the expense of such operations from 60% to 70%. When pulling the affair from the casing the spring 8' acts as a buffer in meeting the swab so that there 35 will be no sudden jars in dislodging and moving the latter such as might otherwise occur and cause a chance parting of the rods.

While I have illustrated and described a 40 preferred arrangement as to detail construction it is to be understood that it is not my intention to adhere strictly thereto since slight changes may be made while accomplishing the desired end.

I claim—

45 1. In pumping mechanism for oil wells, the combination with a casing and reciprocating means adapted to be inserted in said casing, of a swab mounted on said means insertable in the casing therewith and normally held in position against and with respect to the latter by frictional engagement and having a bore, said means extending through the bore and adapted to reciprocate therein with respect to the swab during pumping operations, and such means including at each side of the swab an extension greater in diameter than the bore whereby the swab is positively moved within the casing during the act of inserting or withdrawing said 50 means.

2. In pumping mechanism for oil wells, the combination with a casing, a reciprocating pumping means in the latter, a valve, said means adapted to operate in said casing, and a tubular portion, of a swab encircling 65 said tubular portion and at its periphery adapted to engage by friction the walls of the casing whereby it will be held normally stationary in the latter, and an elastic member interposed between one end of the swab and a lateral extension of said means and spaced from said swab.

3. In pumping mechanism for oil wells, the combination with a casing and a reciprocating pumping means, including a valve, 75 said means adapted to operate in said casing and including a tubular portion, of a swab encircling said tubular portion and at its periphery adapted to engage by friction the walls of the casing whereby to be normally held stationary in the latter, and an elastic member interposed between each end of the swab and a lateral extension of the said means.

4. In pumping mechanism for oil wells, 85 the combination with a casing, and a tubular pumping means adapted for insertion into said casing spaced from the casing walls including a valve, of a swab encircling the said tubular pumping means and having therein 90 a tube through which said means extends in a smooth working fit, said swab being of an elastic nature whereby to conform to the walls of the casing and to frictionally engage the same and held normally fixed with respect 95 thereto, said swab filling the space between the means and casing walls, said means adapted to reciprocate within the swab and with respect thereto in the oil pumping operation.

5. In pumping mechanism and casing 100 cleaning device for oil wells, the combination with a casing, of a swab snugly fitting the walls of said casing held by friction to be normally stationary in the same and having a bore, a length of tubing fixed in the 105 bore, pumping means comprising a valving mechanism and a tube carrying the same, the tube of said means adapted to slidably fit the tubing of the swab and to reciprocate therein with respect to it and the swab, a 110 spring on the tube of the said pumping means at each side of the swab adapted to receive the latter against it as the means is inserted into or withdrawn from the tube whereby the said swab is moved relatively 115 to said casing, and means to fix one end of each spring against movement relatively to said tube of the pumping means.

In testimony whereof I affix my signature.
ARTHUR C. LA COUR.
